Inventor

Filed December 11, 1947. Patented Sept. 23, 1952. Serial No. 831,350. Continuation-in-part of application filed Sept. 10, 1946, Serial No. 7,370, now abandoned.

For a description of the invention in its original and complete form, reference is made to the original specification, which is incorporated by reference, and to the drawings, which are a part of the original specification.

UNITED STATES PATENT OFFICE

2,611,415

HEATED TOILET SEAT

Junior S. Ryland, Santa Barbara, Calif.

Application June 6, 1949, Serial No. 97,455

2 Claims. (Cl. 155—1)

This invention relates to new and useful improvements and structural refinements in toilet seats, and the principal object of the invention is to assure comfort of the person occupying the same, this being of particular importance in connection with toilet seats used by small children, although the invention may, of course, be employed by adults as well.

The above mentioned object is achieved by the provision of a heated toilet seat, in other words, a hollow seat providing a chamber to receive a liquid heating agent such as hot water, so that the body of the seat is maintained at a warm degree of temperature, preferably that of the human body, thus assuring comfort of the user, particularly small children who generally find a cold toilet seat objectionable and thereby develop a tendency to resist the use of a toilet.

I am aware that heated toilet seats have been designed in the past, some heated electrically and others heated by water delivered thereto by flexible tubing from a hot water pipe in a bathroom, or the like, in which instances the toilet seat was a permanent part of the toilet apparatus and could not always be employed without discarding the conventional, unheated seat and sustaining the cost of the heated version. My invention, therefore, seeks to eliminate this disadvantage by providing a warming device in the form of a toilet seat which is adapted for positioning on a conventional toilet seat and which may be filled with water and emptied in the manner of a "hot water bottle," thus being adapted as a convenient and an inexpensive accessory for any conventional toilet equipment.

The invention may, of course, be manufactured in different sizes so as to suit children as well as adults, and some of the advantages of the invention reside in its simplicity of construction, in its pleasing appearance, and in its adaptability to economical manufacture.

With the above more important objects and features in view and such other objects and features as may become apparent as this specification proceeds, the invention consists essentially of the arrangement and construction of parts as illustrated in the accompanying drawings, in which:

Figure 1 is a side elevational view of the invention in situ on a conventional seat of a toilet;

Figure 2 is a top plan view of the invention per se;

Figure 3 is a cross sectional view, taken substantially in the plane of the line 3—3 in Figure 2;

Figure 4 is a cross sectional view, taken substantially in the plane of the line 4—4 in Figure 2;

Figure 5 is a rear elevational view of the invention per se;

Figure 6 is a fragmentary cross sectional detail, taken substantially in the plane of the line 6—6 in Figure 3;

Figure 7 is a perspective view of a guard used in the invention;

Figure 8 is a top plan view showing a modified embodiment of the invention;

Figure 9 is a cross sectional detail, taken substantially in the plane of the line 9—9 in Figure 8; and

Figure 10 is a fragmentary cross sectional detail, similar to that shown in Figure 3, but illustrating another modified embodiment.

Like characters of reference are employed to designate like parts in the specification and throughout the several views.

Referring now to the accompanying drawings in detail, more particularly to Figures 1—7 thereof, the invention consists of a warming device for toilet seats, designated generally by the reference character 10 and embodying in its construction a hollow body 12 which conforms substantially to the configuration of a conventional toilet seat 14 and is adapted to be super-imposed thereon, as shown in Figure 1.

The hollow body 12 provides a chamber 16, and

it is to be noted that the rear portion of the body is formed integrally with a protuberance 18, which, in turn, is provided with a pair of outwardly projecting bosses 20, 22, disposed in side-by-side or juxtaposed relation, as is best shown in Figure 6.

The boss 22 is provided with a screw threaded bore 24 which constitutes an inlet port, so to speak, whereby hot water may be poured into the chamber 16, to which end the outer portion of the

boss 22 may be flared outwardly as at 26, so as to provide a funnel, so to speak, as will be clearly apparent.

A suitable filler plug or screw 28 is receivable in the bore or port 24, constituting a closure for the same.

Similarly, the aforementioned boss 20 is provided with a screw threaded bore 30 constituting an air vent port which is equipped with a closure in the form of a vent plug 32, and as is best shown in Figures 3 and 6, the vent port 30 communicates at its inner end with an adaptor 34 to which, in turn, is connected a vent tube 36. This tube is disposed entirely within the chamber 16 and extends around one side of the seat body 12 to the

front portion of the seat body, at which point, in-

dicated at 38 in Figure 2, the tube is open and communicates with the chamber 16.

It will be observed from the foregoing that the water inlet port 24 communicates with the chamber 16 in the rear region of the seat body while the vent pipe 36 communicates with the chamber in the front region of the seat body, filling of the chamber 16 with water being facilitated by simply removing the entire device from the conventional toilet seat 14 and removing the plug 28, after which water may be poured into the chamber 16 through the port 24. On the other hand, after the water has cooled and the chamber 16 is to be emptied, the plug 28 as well as the plug 32 are removed, so that water may be poured outwardly through the port 24 while air may pass into the chamber through the port 30 and the tube 36, to displace the out-flowing liquid.

If desired, particularly in instances where the device is to be used by small children, the front portion of the seat body may be equipped with a removable guard 40, attachable to the seat body by a pair of resilient clips 42 (see Figure 7), and in addition, an arcuate back rest 44 may be removably attached to the rear portion of the seat body 12 by a plurality of screws 46, or the like, this guard and back rest being heated by the heating agent in the chamber 16, by the thermal conductivity of the body 12.

Referring now to the modified embodiment of the invention illustrated in the accompanying Figures 8 and 9, this is designated generally by the reference character 50 and consists of a warming device in the form of a hollow body 52, provided, if desired, with a guard 54 and a back rest 56 and also equipped in the rear portion thereof with a filler port and plug, the latter being illustrated at 58 in Figure 8.

However, in this instance, it is the front portion of the seat body which is provided with a vent port 60 and a vent plug 62, and since the filler plug and the vent plug, in this instance, are located in relatively opposite regions of the seat body, the use of the aforementioned vent tube 36 is eliminated.

It is to be noted that the invention may be made of any suitable material, including foldable material, such as would permit the device to be folded or collapsed for compact storage or for convenience while traveling.

Finally, in another modified embodiment of the

invention shown in Figure 10, the back rest 70 is hollow and is formed integrally with the main body 72, so that the heating agent in the latter may also fill the interior of the back rest and warm the same.

It is believed that the advantages and use of the invention will be readily understood from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

1. As an article of manufacture, a hollow toilet seat providing a chamber for the reception of a liquid heating agent whereby the body of the seat may be heated, said seat having a filled port and a vent port communicating with said chamber, a filler plug and a vent plug provided in the respective ports, and a hollow back rest provided on said seat in communication with said chamber.

2. A warming device adapted to be detachably disposed upon a toilet seat comprising a hollow endless body adapted to receive a heated fluid, a fluid inlet port in said body, said body having a crescent shaped hollow back rest carried by the rear portion thereof and communicating with said hollow body.

JUNIOR S. RYLAND.
